WILLIAM BALLARD, OF LAPEER, NEW YORK.

Letters Patent No. 79,186, dated June 23, 1868.

IMPROVED CARRIAGE-BRAKE.

The Schedule referred to in these Letters Patent and making part of the same.

TO ALL WHOM IT MAY CONCERN:

Be it known that I, WILLIAM BALLARD, of Lapeer, in the county of Cortland, and State of New York, have invented a new and useful Improvement in Carriage-Brake; and I do hereby declare that the following is a full, clear, and exact description thereof, which will enable those skilled in the art to make and use the same, reference being had to the accompanying drawings, forming part of this specification, in which—

Figure 1 is a top view of my invention, with the bolster off the forward axle, leaving the hounds and axle bare, to show its construction.

Figure 2 is a side view of my invention, taken in a line parallel with the forward axle.

Figure 3 is a side view of the tongue and forward end of hound, showing upper and lower straps connecting tongue and hound.

Figure 4 is a forward or back view of rear or ground-brake.

Similar letters of reference indicate like parts.

In the accompanying drawings A A are extensions (upon either side) of the hound-bolt, which connects hound and tongue. b b are elbows or cranks of the same, with pads or brake-blocks attached. c c are iron rods, fastened to the axle and supporting a a. d e d e are pins in the brake-blocks, to prevent their turning over while backing carriage, and to bring them to their places when the carriage moves forward. f is the rod, running from g to i, and connecting the crank in hound with the sliding plates k k. g is the crank, formed by a bend in the hound-bolt, for the purpose of applying the power to my brake. h are the slots in the sliding plates k k, which allow the said plates to slide backward or forward, as desired. i is the pin or bolt which fastens the rod f with the slotted slides k k. j j are the hound for the hound-bolt to pass through, and o are similar straps on the under side of the tongue, for a similar purpose, thereby connecting tongue and hound. l is the rod which connects the forward brake with back or ground-brake m. m, the back or ground-brake, the top or head of which is shown in fig. 1, is more particularly shown and explained in figs. 2 and 4, fig. 2 showing the side thereof, m representing the upper joint or part thereof, and t the lower part thereof. This lower part works on the pivots, having and showing a slot or slide at the same place; this is to allow this portion of the brake to slide up or down, as occasion may require, and also to form a knee or joint, to allow the carriage to be backed without being retarded by this part sticking in the ground. p is a cylinder, enclosing spiral coil spring fastened to the clog or shoe r, so contrived as to allow the same to work up or down, as the necessity requires. t is fastened to p by means of a screw at the end thereof, being so constructed for putting thereon a sharp gouge or pointed shoe, if desired or preferred.

My brake is so constructed as to use both the wheel-brake and the ground-brake at the same time, or, if preferred or desired, the wheel-brake only. This is done by simply drawing the pin or bolt i, thereby detaching the back or ground-brake from the power and taking it off. This wheel-brake operates in such manner that when the team is drawing, the brake-blocks are instantly thrown off. When backing, the brake-blocks turn up and do not interfere therewith, but when the wheels are moving in the direction of the front, and the carriage or load presses against the team or power, they throw the brake-blocks against the forward part of the wheels instantly, and if the back or ground-brake is attached, that is also as promptly thrown against the ground. In backing, the ground-brake, if on, is thrown up like the knee, and does not interfere therewith. This portion of the brake is more particularly adapted to icy places, as it assists in preventing the carriage sliding sideways, and may also be applied to sleds or sleighs by attaching the principle shown at g to the rollers thereof.

I do not claim the peculiarity in the brake-blocks as my invention, but I claim the privilege of using a spring attached thereto, for the purpose of throwing said blocks back after backing the carriage; but having thus described my invention,

What I claim as new, and desire to secure by Letters Patent, is—

1. The bent hound-bolt or crank, as described, and fastened to hounds and tongues by means of iron straps *j* and *o*, also the said manner of fastening, as herein described, and for the purposes set forth.
2. Also the rod *f*, connected with slides *k* *k*, (slots or slides,) and with rod *l* and brake *m*, in four parts, *m*, *t*, *p*, and *r*, with slides, slots, and spiral coil springs, in combination with crank-hound bolt *g* and other parts herein mentioned and claimed, substantially in the manner and for the purposes herein described and set forth.

The above specification of my invention signed by me, this 2d day of March, 1868.

WILLIAM BALLARD.
